UNITED STATES PATENT OFFICE.

HARRY WARD LEONARD, OF BRONXVILLE, NEW YORK.

RESISTANCE DEVICE.

977,456.

Specification of Letters Patent.

Patented Dec. 6, 1910.

Application filed March 29, 1909. Serial No. 486,297.

To all whom it may concern:

Be it known that I, HARRY WARD LEONARD, a citizen of the United States, residing at Bronxville, in the county of Westchester 5 and State of New York, have invented certain new and useful Improvements in Resistance Devices, of which the following is a full, clear, and exact specification.

This invention relates to devices in which 10 electric energy is intentionally converted into heat.

One of the devices to which my invention is applicable is a field rheostat for a large generator. It is, however, capable of application in other relations.

Among the principal objects of my invention are reduction of first cost; reduction of weight; reduction in the number of parts; the employment of resistive material of 20 very low temperature coefficient, light in weight and of large surface, strong in resisting strains of usage and non-oxidizing; simplicity, ease, cheapness and expedition in making renewals or repairs; an economical and efficient arrangement of the resistance so as to reduce the maximum temperature of many of the parts as will appear hereinafter.

In the preferable embodiment of my invention I employ a plurality of unit resistances arranged in series and I employ a plurality of such series. For example, I may, in a rheostat, arrange the resistance units in two concentric circles, the movable contact lever of the rheostat being pivoted in a central point and having a moving contact at one end making connection with the outside circle of unit resistances and having a moving contact at the other end making 35 connection with the inside circle. Thus the movable contact element acts as a bridge carrying the current across from one circle to the other so that the steps of one circle which are in circuit are in series with steps 40 of the other circle of unit resistances. By this arrangement what may be conveniently called "hot spots" are developed at opposite sides of the rheostat and remote from each other. By the term "hot spot" I refer to 45 that portion of the rheostat lying between one end of the movable arm and the point at which current enters or leaves the device, each of these spots, when the arm is partially turned on, carrying current and being therefore hot while the other portions of the 50 rheostat will not carry current and will

therefore be comparatively cool. In a tapered current rheostat, such as a field rheostat, the heated step next to the movable element is hotter than any preceding one 60 and hotter than it itself will be in any other position of the movable element. In such an application a large number of steps are required and the development of two hot spots as indicated gives an increased capacity for 65 a certain size and weight because of the improved facilities for dissipating the heat generated by the passage of current through the rheostat. Preferably the moving contacts at the opposite ends of the contact lever are 70 independently movable so as to adjust themselves to the contacts over which they are respectively passing.

The specific design referred to gives a perfect distribution of the heat generated in 75 the rheostat circuits secures a very compact rheostat and by using a movable contact element in the form of a double connected contact lever, the friction on the pivot is reduced because of the balanced pressure on 80 the shoes at the two opposite ends of the lever. Moreover, it is unnecessary to carry current through any moving contact except the contact shoes themselves, whereas in customary forms either the pivotal contact carries the current or there are additional metal arcs and corresponding moving contacts, all 85 of which are rendered unnecessary by the present construction. These advantageous features are of especial importance in connection 90 with remote controlled rheostats for many reasons, one of which is that a small amount of power is required to move the contact lever, while the moving contacts are self-adjusting and self-cleaning. 95

The construction of the resistance units, considered individually, gives rise to numerous advantages of which the following may be referred to.

The cost is low because very thin ribbon-like, resistive conductor can be used, the total weight being very small and the cost of labor needed to assemble the parts into a rheostat is comparatively little.

Each of the units is very light in weight 100 because of the weight of the resistance material which may be made extremely light and there is a minimum weight of the other parts necessary.

A much more constant resistance is obtained than with cast iron or other customary forms, because the temperature co- 110

efficient of the resistance ribbon is very low and there is a minimum length of copper or similar conductor.

Owing to the simple construction, the chances of troubles due to connections are greatly reduced while there is no possibility of short-circuits between connecting or lead wires as they are entirely eliminated.

The construction makes it readily possible to get an extremely wide range in the ohms and amperes of a step, and also, when needed, a sufficient range in wattage per step. By varying the width and thickness of the ribbon used, the resistivity of the alloy employed, and the length of the unit, it becomes readily possible to get any variation in ohms with any desired amperes and any desired watts per step within the desirable limits of commercial practice.

The insulation of the resistive conductor can be made extremely high because the metal parts are all supported by high grade insulating material, such as porcelain and it is not necessary to rely at all upon rubber, asbestos, mica, cements, or any of the many forms of commonly employed insulating materials, which are likely to depreciate in time or become affected by moisture, dust, or other insulator-affecting substances or conditions.

The ribbon form of resistive conductor lends itself readily to securing ample and reliable contact between the resistive material and the strap-like copper terminal pieces employed, without the necessity for soldering, which is likely, in many cases, to depreciate the quality of the materials soldered.

It is readily possible to inspect, remove, replace, repair, modify or adjust the unit resistances or any of their parts and, since many of the parts are interchangeable and uniform independent of the ohms, amperes or watts of the steps, only a few repair parts are necessary to make any repairs needed. A few parts and a small inexpensive lot of sheet German silver of several different thicknesses, make it possible for any workman in a few minutes, with ordinary tools, to make repairs, or, in fact, to make new units of any desired electrical properties within very wide limits.

The chance of breakage of the resistive material due to shocks in shipment, installation or use, is greatly reduced as compared with cast iron grids or any usual forms of resistances for relatively large currents.

The strains due to heating and cooling of the resistive material are reduced to a minimum and practically eliminated, whereas in cast iron grids or other familiar types of resistances, these strains are frequently destructive or troublesome.

The risks of breakdown of insulation due

to lightning or high voltage discharges, are reduced to a minimum because of the permanent reliable character of the insulation and the large air spaces.

The risks of short-circuits or leakage between the different parts of the rheostat, such, for instance, as those due to oil, dust, filings, mud, ice, or condensed moisture on the surface, are reduced to a minimum.

The form of the unit, its method of mounting, and its position with relation to the face of the support, result in an extremely compact construction and most advantageous form for the distribution of the heat generated in the most advantageous manner.

The employment of a resistive conductor in the form of a ribbon which has been reflexed and then put under tension, makes it possible to use the thinnest obtainable ribbon and yet have it hold its position when heated and cooled in practice.

The form of resistance is such as to reduce any inductive effects to a minimum.

In the accompanying drawings, which illustrate the invention, Figure 1 is a side elevation of a resistance unit. Fig. 2 is also a side elevation viewed from a point ninety degrees removed from the view-point of Fig. 1. Fig. 3 is a bottom plan view of the unit. Fig. 4 is an enlarged section on line 4-4 of Fig. 2, looking in the direction of the arrow. Fig. 5 is a partial vertical section on the line 5-5 of Fig. 1, looking in the direction of the arrow. Fig. 6 is an elevation of the lower end of the unit looking in the direction of the arrow 6 in Fig. 1. Fig. 7 is a perspective view of one of the unit terminals. Fig. 8 is a perspective view of another of the unit terminals. Fig. 9 is a bottom plan view of the rheostat partly broken away, showing the manner of application of the resistance units thereto. Fig. 10 is a top plan view of a rheostat showing the stationary contacts and the movable contact element. Fig. 11 is a diagram of the electric connections through the rheostat. Fig. 12 is a bottom plan view of one end of the movable contact element showing the contact shoe; and Fig. 13 is a partial section on the line 13-13 of Fig. 12. Fig. 14 is an enlarged perspective view of the bottom portion of the unit.

Referring to the drawing and first to Figs. 1 to 8 inclusive and 14, each unit comprises a support, consisting of the porcelain insulating elements at its ends which are adjustably supported by the metal rod 1. At one end the element consists of two spools 3 and 4 through which extends a metal bolt 5, this bolt extending through an eye 6 of the metal rod 1. The porcelain insulating element at the other end of the unit consists of a porcelain block 7 through which the screw threaded portion 8 of the rod 1 extends. This element is secured upon the rod 1 by means of 130

the nut 9, while it is held from moving toward the support at the other end of the unit by means of the nut 10. It will be apparent that the distance between the elements 5 may be adjusted by adjusting the nuts 9 and 10 upon the rod 1 and that this adjustment is along the line of greatest dimension of the unit. The resistive conductor 11 of the unit is ribbon-like, flexible, 10 flexed (as shown best in Fig. 1) and is of non-oxidizable material, such as German silver. One end of this conductor passes within a loop 12 of conducting material such as copper, and also within this loop is 15 inserted an end of the terminal 13, also of copper and the screw 14 is passed through the loop, the terminal and the resistive conductor. A lock nut 15, bearing upon a washer 16, firmly clamps the terminal, loop 20 and conductor together. The porcelain block 7 is provided with a recess 17 for the reception of the nut 15, washer 16. The end of the conductor, together with the terminal 13 is secured to the block 7 by means 25 of a nut 18 upon the screw 14, the screw passing through the block 7 and the nut 18 being within the recess 19 upon the opposite side of the block. From the terminal 13 the resistive conductor passes upwardly to the 30 spool 4 and down to the opposite side of the block 7. Here the conductor is bent at right angles to extend along the block, this portion extending along the block being indicated by the numeral 11'; then it extends 35 upwardly and over the spool 3 and downwardly again to the block 7 and terminates at the terminal 20. Preferably the conductor assumes the form of a long narrow arch as shown in Fig. 1. For convenience we 40 will call the side of the block 7 upon which the terminals 13 and 20 are located, the front side. Terminal 20 and the extremity of the resistive conductor are secured to the front of the terminal block in precisely the 45 same way as described in connection with the other extremity of the conductor and the terminal 13. On the back side of the block 7 the resistive conductor is surrounded by a loop of copper 21 and within this 50 loop and next to the resistive conductor is entered the elongated part 22 of terminal 23. This part 22 of the terminal 23 is substantially of the same length as that portion of the resistive conductor where it is at right 55 angles to its major length and the resistive conductor and terminal 23 are clamped together by bolts 24 and 25 which pass through the loop 21, the resistive conductor, and the part 22 of the terminal 23. The 60 terminal 23 is held in position by the nut 9 and the rod 1 which extends through it. The head of the bolt 25 extends into the recess 26 and correspondingly the head of the bolt 24 extends into the recess 19. The recesses 19 and 26 are deep enough so that the

bolts 24 and 25 do not come in contact with the screw 14 and the similar screw for securing the terminal 20 in position. In order to make certain, however, of the insulation between these bolts and screws, mica disks 27 and 28 may be placed in the recesses as shown. It will be observed that the terminal 23 is not in the same plane with the terminals 13 or 20. In this way contact of the terminals is avoided with economy of lateral space. The block 7 is provided with a rib 29 between the terminals 20 and 13, thereby insuring good insulation between them and preventing accidental contact between them both by preventing the terminals from being accidentally pushed together and also by increasing the surface over which contact might be formed by dust, oil, or the like. The parts having been assembled as described, it will be apparent that the resistive conductor may be stretched between the resistance elements at the ends of the unit by adjusting nuts 9 and 10 and that the conductor being placed under tension any slack which might otherwise be occasioned by heating of the conductor will be taken up so that the conductor will be maintained in proper position, regardless of its temperature. The terminals 13, 20 and 23 are made of stiff copper sheet, so that they are adapted to support the unit and in assembling any device in which the units are employed, it is not necessary to furnish any further support for the units than to secure these terminals in such manner as to establish the desired electrical connections.

Referring to Figs. 9 and 10, it will be seen that the series of stationary contacts, 30, are arranged in a circle upon the supporting plate 31, which is preferably of slate or other suitable insulating material. Concentric with the series 30 is arranged a second series of stationary contacts 32. Pivoted at 33 is a movable contact element 34 which, at its ends, carries a contacting device 35 adapted to engage with the series 30 of stationary contacts while at the other end of the element 34 is a device 36 adapted to engage with the contacts of the series 32. The contact element 34 is of conducting material, or a conductor may be laid along it so as to electrically connect the devices 35 and 36 so that electrical connection is established along the lever or arm 34 between the two series of contacts 30 and 32. Upon the opposite side of the plate 31 are arranged the resistance units as before described, this arrangement being as shown in Fig. 9, from which it will be seen that the resistance units 120 are arranged in concentric circles to correspond with the series of stationary contacts. The stationary contacts may be secured in position by means of bolts 37 which extend through the plate 31 and project from the 125 130

rear thereof. The resistance units are then secured in position by placing their terminals, 13, 20 and 23 so as to embrace the bolts 37 when they can be secured thereto by nuts 5 in a well-known manner. It is to be observed that as the unit terminals are adapted to support the unit and to furnish electrical connection to the resistive conductor thereof, that the securing of the unit as described, 10 not only mechanically secures but electrically connects the same. As shown in Fig. 9, the adjacent terminals of adjacent units in the same circle are connected to the same bolt and therefore a continuous connection 15 is established through the resistive conductors of all the units of the circle and the resistive conductor of each unit is connected to three of the stationary contacts, these connections being made at the extremities of 20 the unit's conductor and at a point intermediate of its end so that there is in each unit two steps of resistive conductor. Of course, by extending this arrangement any number of steps might be provided in the unit. 25 The construction of the contact devices 35 and 36 is shown in details in Figs. 12 and 13. Each of these devices comprises a plurality of skate-shoes 38, rectangular in outline and comparatively long and narrow 30 and with curved ends extending lengthwise across the arm; that is, the shoes extend lengthwise in the direction of movement. Each shoe is pressed against the stationary contacts by a spring 39 at each end. Each 35 spring is partly inclosed in a tubular case 40 which has a closed, rounded outer end, which case sits in a considerably large aperture in the shoe. The spring and its case extend into a considerably larger hole 40 drilled in the lower face of the pivoted arm, there being one hole for each spring. A flexible conductor 41 is secured to each shoe and also to the contact arm, giving direct electrical connection between these parts. 45 The above construction secures excellent contact between the shoes and resistance contacts, gives uniform pressure and will permit the parts to be readily renewed or replaced. This construction gives a flexible 50 form of skate-contact which rides readily over any unevenness upon the stationary contacts without breaking the circuit or seriously affecting the contact. It will be seen that the contacts at the ends of the lever arm are independently movable and that 55 the arm is balanced upon its pivot, being supported at both ends. It is thus easily turned even though the surface over which the contacts ride is uneven, due to arcing or 60 other causes, not only because of the balancing feature, but because the skates are of such construction as to obviate such engagement of stationary and movable contacts that movement might be prevented. These

considerations are of peculiar importance 65 in connection with rheostats which are controlled from a distance.

The connections established by the rheostat are diagrammatically shown in Fig. 11 in which the rheostat is shown as connected 70 to the conductors 42 and 43 in the circuit the current of which is to be controlled. It will be apparent from the position of the contact arm as shown that the circuit will be from the conductor 42, through the resist- 75 ance 44, connected to the series 30 of stationary contacts, through the contact arm to the series of stationary contacts 32, thence through the resistance 45 connected through this second series of stationary contacts to 80 the conductor 43. The current will thus pass through sections of the resistance in the two concentric circles as indicated by "hot spot" and it will be noted that these hot spots are located upon opposite sides of 85 the rheostat so that the heat generated may be freely radiated and a compact construction obtained.

While the invention has been illustrated in what is considered to be its best embodiment, it may be embodied in other constructions and is not, therefore, limited to the structure shown in the drawings.

Having thus described my invention, I declare that what I claim as new and desire 95 to secure by Letters Patent, is:—

1. The combination with a removable resistance unit comprising a flexible resistive ribbon, metallic terminal contact pieces connected to the two ends of said ribbon respectively, a supporting block of insulating material secured to said terminal contact pieces, of a support for said unit, said contact pieces being adapted to be removably attached to said support and when so attached to support the unit as a whole, said ribbon being freely exposed to the air throughout the greater part of its length.

2. The combination with a removable resistance unit comprising a flexible resistive ribbon freely exposed to the air, and metallic terminal contact pieces connected to the two ends of the ribbon respectively, of a common support which said contact pieces are adapted to be attached to or removed from, said terminal contact pieces being adapted when attached to said support to support the unit as a whole and to permit the removal of said unit as a whole.

3. A removable resistance unit having 120 greater length than breadth so that it is long and narrow, said unit comprising two terminal contact pieces at the same end of the unit and comprising a ribbon-like resistance connecting said terminal contact pieces, said contact pieces adapted to be attached to a common support and to support the unit as a whole relative to said common support.

4. A rheostat or heater comprising a plurality of removable resistance units, each of said units comprising a flexible resistive conductor, a support therefor and a plurality of 5 terminal contact pieces adapted to support the unit as a whole and permit the ready removal of the unit as a whole.

5. A removable resistance unit comprising a metallic support extending along the 10 greatest dimension of said unit, insulating pieces carried by said support at a distance from each other, terminal contact pieces adapted to jointly support said unit as a whole, and a metallic resistance ribbon having its ends connected to said terminal contact pieces respectively.

6. A rheostat or heater comprising in combination a support and a plurality of individually removable resistance units mounted 20 thereon, each of said units comprising a flexible resistive conductor and means for adjusting the tension upon said conductor.

7. A rheostat or heater comprising a plurality of individually removable resistance 25 units, each of said units comprising a metal element for supporting the parts of the unit, said parts including a plurality of insulating elements, and a flexible, ribbon-like resistive conductor stretched between said insulating elements.

8. A rheostat or heater comprising a plurality of individually removable resistance units, each of said units comprising a metallic resistive conductor freely exposed to the 35 air, a support for the same comprising insulating elements and means for adjusting the distance between said elements.

9. In a rheostat or heater, the combination 40 with a reflexed metallic resistive conductor freely exposed to the air, said conductor being in the form of a long narrow arch, and a support for the same comprising insulating elements and means for adjusting the distance between said elements.

45 10. In a rheostat or heater, the combination with a reflexed metallic ribbon-like resistive conductor freely exposed to the air, said conductor being in the form of a long narrow arch, and a support for the same comprising insulating elements and means for adjusting the distance between said elements.

11. In a resistance device, the combination 55 with a metallic support, of two porcelain elements supported by said metallic support and adapted to act as insulating supports, and a resistive conductor stretched between said porcelain elements and outside of said metallic support.

60 12. In a rheostat or heater, the combination with an insulating support, of contacts thereon, a contact member movable over said contacts to cut out or insert a step of resistance as it moves from one contact to the

next, and a plurality of resistance units each 65 comprising a support and a resistive ribbon conductor thereon constituting a plurality of steps and connected to three of said contacts.

13. A rheostat or heater comprising a plurality of resistance units, each of said units comprising a central support, a ribbon-like resistive conductor removably secured to said support at the ends of the unit, said conductor being freely exposed to the air except at the ends of the unit where it engages 75 the support.

14. In a rheostat or heater, the combination with a suitable support, of contacts thereon, a contact member movable over said 80 contacts to cut out or insert a step of resistance as it moves from one contact to the next, and a plurality of individually removable resistance units each comprising a support and a resistive conductor thereon constituting a plurality of steps, the terminals 85 of the steps being arranged at the same end of the unit.

15. In a rheostat or heater, the combination with a suitable support, of contacts 90 thereon, a contact member movable over said contacts to cut out or insert a step of resistance as it moves from one contact to the next, and a plurality of resistance units each comprising a support and a resistive ribbon conductor thereon constituting a plurality of steps, the terminals of the steps being arranged at the same end of the unit.

16. In a rheostat, the combination with a series of stationary contacts, of a support 100 therefor, a series of resistance steps corresponding to said contacts and comprising flexible resistive conductors arranged in the form of long narrow arches, and means for supporting said arches in a position such that a line parallel to the sides of an arch and passing through the center thereof will be substantially normal to the surface in which the stationary contacts lie.

17. In a rheostat, the combination with a 110 series of individually removable resistance units each comprising a ribbon-like resistance, of a series of contacts therefor, a second series of individually removable resistance units each comprising a ribbon-like resistance, a second series of contacts therefor and a resistance-varying movable element adapted to act as a conducting bridge between the two series of resistance steps, and means for moving said movable element to 120 vary the resistance.

18. In a rheostat, the combination with a series of steps of resistance, of a series of contacts therefor, a second series of steps of resistance, a second series of contacts therefor and a resistance-varying movable element adapted to act as a conducting bridge between the two series of resistance steps, 125

and means for moving said movable element to vary the resistance, said movable element having a plurality of independently movable contact shoes corresponding to the series of resistance contacts.

19. A rheostat or heater comprising a plurality of individually removable resistance units, each of said units comprising a support and a flexible resistive conductor thereon, the unit having one dimension greater than the others and its resistive conductor being substantially parallel to the greatest dimension throughout the greatest part of the length of the conductor.

15 20. A rheostat or heater comprising a plurality of resistance units, each of said units comprising a support, a flexible resistive conductor thereon, and terminals connected to said conductor at one end of the unit, said terminals being adapted to jointly support the unit as a whole.

21. In a rheostat or heater, the combination with a plurality of contacts, of an insu-

lating support therefor, a movable contact element adapted to move over said contacts and a plurality of resistance units connected to said contacts, each of said units comprising a support and a flexible resistive conductor thereon, and each of said units being supported with its greatest dimension substantially at right angles to the plane of said support.

22. A resistance unit having a metallic ribbon so arranged as to have two sections of the ribbon substantially parallel to each other and a support for said ribbon, said support being between the said sections and the greatest dimension of said support being substantially parallel to the said sections of said ribbon.

In testimony whereof I affix my signature, in presence of two witnesses.

H. WARD LEONARD.
